UNITED STATES PATENT OFFICE.

HARRY WRIGHT, OF COLUMBUS, OHIO, ASSIGNOR TO THE BUCKEYE
MALLEABLE IRON AND COUPLER COMPANY, OF COLUMBUS,
OHIO.

FURNACE-CHARGING BOX.

SPECIFICATION forming part of Letters Patent No. 788,010, dated April 25, 1905.

Application filed September 23, 1903. Serial No. 174,357.

To all whom it may concern:

Be it known that I, HARRY WRIGHT, a resident of Columbus, in the county of Franklin and State of Ohio, have invented certain new and useful Improvements in Furnace-Charging Boxes; and I do hereby declare the following to be a full, clear, and exact description of the invention, such as will enable others skilled in the art to which it appertains to make and use the same.

My invention relates to an improved furnace-charging box, the object of the invention being to provide a charging-box comprising one integral casting which is a stronger, cheaper, and more durable box than the boxes heretofore made; and with this object in view the invention consists in certain novel features of construction and combinations and arrangements of parts, as will be more fully hereinafter described, and pointed out in the claims.

In the accompanying drawings, Figure 1 is a top plan view illustrating my improvements. Fig. 2 is a broken side view. Fig. 3 is an end view, and Fig. 4 is a view in cross-section.

My improved box 1 comprises one integral casting forming a rectangular box, having sloping side and end walls 2 and 3 and flanged all around its upper edge, as shown at 4. The bottom 5 and forward end 3 are perforated, as shown at 6. On the opposite end of the box a pocket 7 is cast integral and is adapted to receive the head of the charging-arm of the ordinary furnace-charging apparatus, and a socket 8 is formed in the end wall 9 to receive the plunger of said charging-arm. This end of the box is strengthened by integral webs 10 and 11, and enlargements 12 are formed at the upper edges of the pocket-wall 40 to further strengthen the device.

A great many slight changes might be made in the general form and arrangement of the several parts described without departing from my invention, and hence I do not restrict myself to the precise details set forth, but consider myself at liberty to make such slight

changes and alterations as fairly fall within the spirit and scope of my invention.

Having fully described my invention, what I claim as new, and desire to secure by Letters Patent, is—

1. A cast-metal furnace-charging box having cast integral with one end thereof, a rearwardly-projected pocketed enlargement, and webs connecting said enlargement with the end of the box.

2. A cast-metal furnace-charging box having cast integral with the rear end thereof, a rearwardly-projecting pocketed enlargement, and webs connecting the rear end of the box with the bottom thereof.

3. A cast-metal furnace-charging box having an integral socketed part projecting inwardly through the rear end of the box, and a rearwardly-projecting enlargement cast integral with the rear end of the box and having a pocket communicating with said socketed portion.

4. A cast-metal furnace-charging box having flaring side and front end walls, and having an integral pocketed enlargement cast on its rear end wall and projecting outwardly therefrom and means for bracing said enlargement.

5. A charging-box made in a single piece and having sloping side walls and a sloping forward end wall, and a pocketed portion at one end of said box and made integral therewith.

6. An end for a furnace-charging box consisting of a casting provided with a socket for receiving the end of the charging-bar, and having strengthening-ribs extending from the upper ends of the side portions of said socket out to and around the corners.

In testimony whereof I have signed this specification in the presence of two subscribing witnesses.

HARRY WRIGHT.
